UNITED STATES PATENT OFFICE.

WALTER R. KAHNS, OF CHICAGO, ILLINOIS, ASSIGNOR TO J. H. WHITE MFG. CO., OF BROOKLYN, NEW YORK, A CORPORATION OF NEW YORK.

SUPPORT FOR INCANDESCENT-ELECTRIC-LAMP SOCKETS.

1,115,206.

Specification of Letters Patent. Patented Oct. 27, 1914.

Application filed May 5, 1914. Serial No. 336,420.

To all whom it may concern:

Be it known that I, WALTER R. KAHNS, a citizen of the United States, residing at Chicago, in the county of Cook and State of Illinois, have invented an Improvement in Supports for Incandescent-Electric-Lamp Sockets, of which the following is a specification.

My invention relates to supports for the 10 sockets of incandescent electric lamps, particularly to that class of lighting fixtures for producing the so-called semi-indirect lighting effects, in which a transparent or translucent bowl is suspended, and the lead wires 15 are brought to one or more lamp sockets fixed within the bowl. In fixtures of this character it is customary to employ hangers to support the bowl, and to connect the supporting arm or bracket for the lamp sockets 20 to such hangers or hooks. In all such cases of which I am aware the supporting arms for the lamp sockets have no adjustability and the lamps must remain in a fixed position relatively to the bowl.

25 The object of my present invention is to so construct the supporting arms for the lamp sockets, that the position of the lamps may be changed at pleasure and fixed in any desired adjusted position within the bowl.

30 The details of the invention are herein-after particularly described.

In the accompanying drawing: Figure 1 is an elevation partially in section, illustrating my invention connected to a hanger attached to a bowl. Fig. 2 is a similar view showing the same attached to a modified form of hanger. Fig. 3 is a plan view of my improved support detached. Fig. 4 is an inverted plan view of the same. Fig. 5 is a plan view illustrating the blank from which one member is formed, and Fig. 6 is a similar view of the other member.

Similar reference characters indicate like parts throughout the several views.

45 1 designates a bowl of glass or other transparent material, such as used in a fixture for producing a semi-indirect lighting effect.

50 2 designates a hanger connected with the bowl 1 in any suitable manner. I have represented the hanger provided with a lug 3, passed through a hole in the bowl beneath its rim, said lug having a reduced end screw threaded to receive a nut 4. The hanger 55 also has a hook 5 at its upper end adapted

to receive the end link of a supporting chain 6.

7 and 8 designate, respectively, the two members comprising my improved socket support. These members are preferably 60 made of brass or other metal, but may be made of any suitable material. I also prefer to make each member of a single piece of metal cut out of the shape shown in Figs. 5 and 6. The member 7 being bent to shape 65 on the dotted lines 9, 10, 11, 12 and 13, and the member 8 on the dotted line 14. The member 7 is provided with a central longitudinal slot 15, enlarged at one end. When the right angled projections at one end of the 70 blank shown in Fig. 5 are bent to shape, they form the guide clip 16, shown in Figs. 1, 2, 3 and 4. The opposite end of this member 7 is provided with a circular opening 17. The member 8 is also provided at one end 75 with a similar opening 18, while its opposite end is preferably somewhat reduced in width and provided with a screw-threaded hole 19, of smaller dimension. This end of the member 8 is adapted to be inserted in the 80 guide clip 16, on the member 7, when the set screw 20 is passed through the enlarged end of the slot 15 in the member 7 and screwed into the small screw-threaded hole 19, in the member 8, thus connecting the two members 85 together in such manner that the member 7 is slideable longitudinally upon the upper surface of the member 8, the screw 20 working in the slot 15 with its head in contact with the upper surface of said member 7. 90 It will be apparent that the member 7 may be fixed at any desired longitudinally adjusted position upon the member 8, by tightening the set screw 20.

In connecting my improved socket support to a lighting fixture, the opening 18 in the member 8 is placed over a lug upon the hanger secured to the bowl, said lug having a screw-threaded projection to receive a suitable nut to clamp the end of said member 8 firmly between it and said lug. 95

In Fig. 1 of the drawing, in addition to the lug 3 and nut 4, for securing the hanger 2 to the bowl 1, I have shown the hanger provided with another lug 21 and nut 22 105 for attachment of the member 8.

In Fig. 2 of the drawing, I have shown the member 8 attached to the same lug and secured by the same nut as employed for attaching the hanger to the bowl. As before 110

remarked, the socket support may be attached to any character of hanger and in any suitable manner.

23 designates a hollow stud exteriorly 5 screw-threaded on its lower part and secured within the opening 17 on one end of the member 7.

24 indicates a lamp socket screwed upon the screw-threaded end of the stud 23, and 10 25 designates an incandescent electric lamp attached to said socket.

26 represents the conductor wires which pass up through the hollow stud 23 and are then looped through the links of the support chain 6.

15 It will readily be seen that the support is capable of lateral adjustment when connected to the hanger, as shown in Fig. 1, and that when connected as shown in Fig. 2, 20 the lamp may be fixed in an inclined or horizontal position. This may be done by loosening the nut 22 or the nut 4 and swinging the support to the desired position and then tightening the nut.

25 By the employment of my invention, the same socket supports may be used upon fixtures of various sizes, as the length of the support can be varied to suit the circumstances, and allow for proper relative arrangement of the lamps, and they can be secured in any desired adjusted position.

30 The end of the screw 20, after it has been screwed into the small screw-threaded hole 19 in the member 8, is preferably upset, 35 which prevents possible loss of the screw, the enlarged end of the longitudinal slot 15, in the member 7, permitting the insertion or withdrawal of the screw-head at that point when it may be desired to connect or 40 separate the two members; the reduced end of the member 8 also aiding in this respect.

I claim as my invention:

45 1. A support for an electric lamp socket, comprising two members each cut out of a flat strip of metal, one of said members having oppositely disposed right angled projections at one end bent over toward each other forming a guide clip, said member being provided with a central longitudinal slot enlarged at one end, a stud secured to the other end of said member for attachment of a lamp socket, the other member 50 having a reduced portion at one end, with a screw-threaded hole therein, a headed screw

secured within said hole and adapted to be 55 passed through the enlargement at the end of the longitudinal slot in said first member and passed along in said slot whereby the two members are held by means of said screw-head and said clip in slidable contact, 60 the free end of said second member being provided with an opening for connection with a hanger.

2. In an electric-lighting fixture, the combination of a globe or bowl, a hanger for 65 suspending the same, a support for an electric lamp socket comprising two members each cut out of a flat strip of metal, one of said members having oppositely disposed right angled projections at one end bent 70 over toward each other forming a guide clip, said member being provided with a central longitudinal slot enlarged at one end, a stud secured to the other end of said member for attachment of a lamp socket, 75 the other member having a reduced portion at one end with a screw-threaded hole therein, a headed screw secured within said hole and adapted to be passed through the enlargement at the end of the longitudinal 80 slot in said first member and passed along in said slot whereby the two members are held by means of said screw-head and said clip in slidable contact, the free end of said second member being provided with an 85 opening for connection with said hanger.

3. A support for an electric lamp socket, comprising two members, one of said members being provided with a guide-clip and longitudinal slot having an enlargement at 90 one end, a stud secured to one end of said member for the attachment of a lamp socket, the other member having a reduced portion at one end provided with a screw-threaded hole and passed through said guide-clip on 95 the first member, a set screw passing through said slot in said first member and screwed into said screw-threaded hole in the second member with its end upset to prevent its withdrawal, the other end of said 100 second member being provided with an opening for connection with a hanger.

Signed by me this 1st day of May, 1914.

WALTER E. KAHNS.
